(57) **CLAIM**

The ornamental design for a cassette clamp for electrophoresis gel casting, as shown and described.

DESCRIPTION

This application is related to U.S. Design patent application Ser. No. 29/545,637, entitled "Rig for Electrophoresis Gel Casting," and filed on a date even herewith, the entire contents of each of which are incorporated by reference herein.

FIG. 1 is a front perspective view of a first embodiment of a cassette clamp for electrophoresis gel casting showing our new design.

FIG. 2 is back perspective view thereof.

FIG. 3 is a front view thereof.

FIG. 4 is a back view thereof.

FIG. 5 is a right side view thereof.

FIG. 6 is a left side view thereof.

FIG. 7 is a top view thereof.

FIG. 8 is a bottom view thereof; and,

FIG. 9 is a front perspective view thereof showing environmental structure.

The broken lines in the figures show unclaimed portions and environmental structure and form no part of the claimed design.
